BEARING PROTECTION DEVICE

Oscar C. Gruender, Milwaukee, Wis., assignor to
Nordberg Manufacturing Co., Milwaukee, Wis.,
a corporation of Wisconsin

Application May 27, 1932, Serial No. 613,872

2 Claims. (Cl. 83—10)

My invention relates to an improvement in bearing protecting means which is particularly applicable for use with gyratory cone crushers. I illustrate it in connection with a gyratory cone 5 crusher in which the crushing head is mounted on a main spherical bearing. One object is the prevention of admission of dust or grit to such main bearing. Another object is the prevention of the admission of dust or grit to the circulation 10 of oil which passes outwardly from said main bearing. Another object is the provision of improved means for employing air to protect the bearings. Other objects will appear from time to time in the course of the specification and 15 claims.

I illustrate my invention more or less diagrammatically in the accompanying drawings, where- 20 in—

Figure 1 is a vertical section;

Figure 2 is a section on the line 2—2 of Figure 20 1; and

Figure 3 is a section on the line 3—3 of Figure 2.

Like parts are indicated by like symbols 25 throughout the specification and drawings.

Referring to the drawings, A generally indicates any suitable base upon which may be mounted the generally cylindrical main frame member A¹ with its bottom flange or flanges A².

30 Mounted upon the upper edge of the main frame A¹ is the tilting ring B with a screwthreaded portion B¹ in mesh with a correspondingly screwthreaded portion B³ of the bowl B². B⁴ is any suitable liner secured to the bowl as by the lugs B⁵ and the bolts B⁶. B⁷ are springs compressed 35 between the bottom of the flange B⁸ about the top of the main frame A¹ and the abutment ring B⁹. B¹⁰ are tension members connecting the ring B with the abutment ring B⁹, whereby the springs B⁷ are effective to hold the ring B normally 40 fixed in relation to the main frame A¹.

C indicates a central bearing member which may be connected as by the spider C¹ to the frame A¹. Rotatable within the bearing C is the eccentric sleeve C² having at its top a gear C³ in mesh with the pinion C⁴ on a drive shaft C⁵, whereby the eccentric sleeve C² may be rotated. C⁶ indicates a gear box formed unitarily with the bearing sleeve C. C⁷ is a cover therefor centrally apertured as at C⁸ in alignment with the eccentric sleeve C². C⁹ is a spherical bearing member mounted upon the cover C⁷. C¹⁰ is an eccentric aperture within the sleeve C².

D indicates a crusher shaft within the aperture 55 C¹⁰. Mounted on the top of the crusher shaft is

the crushing head D¹ upon which is any suitable crushing mantle D² which may be held suitably in position thereon as by any suitable locking sleeve D³. The head is formed with a spherical lower bearing surface D⁴ conforming to and opposed to the bearing member C⁹. The main weight of the head is borne by these opposed bearing surfaces.

In order to protect the main bearing thus formed I surround the periphery thereof with a 5 maze. It may include for example the cylindrical ring E depending from the head and fairly closely surrounding the bearing surface D⁴. It penetrates within an oil sump E¹ formed in the cover plate C⁷ and from which extend oil runoff passages E² to carry off oil which escapes over the edge of the bearing member C⁹. Positioned about the cylindrical maze member E but located upon the cover plate C⁷ is a similar cylindrical member E³. Exterior to it are the interpenetrating or overlapping members E⁴ E⁵ formed on the head D¹ and the cover plate C⁷ respectively. They approach fairly closely but do not contact.

E⁶ is an additional surrounding apron extending from about the outer lower edge of the 25 head D¹.

Formed in the cover plate C⁷ is a circumferential air chamber G which may be closed as by the surrounding plate G¹ to leave an annular air discharge aperture G², which may be gauged and 30 kept uniform as by a plurality of webs G³ about the member E⁵, whereby air under pressure may be directed against the outer surface of the member E⁴ on the head. It will be noted that the surface of E⁴ is inclined in relation to the direction 35 of the air discharged through the aperture G². Any suitable means may be employed for delivering air to the chamber G, as for example the air passages G⁵, the aperture or apertures G⁶ in the gear case C⁶, and the apertures G⁷ in the 40 cover plate C⁷. The arrows in Figure 3 indicate generally the direction followed by the air, it being understood that the aperture directs a circumferential sheet of air at high speed against the inclined outer face of the member E⁴. This 45 air then escapes downwardly and outwardly along the inner face of the member E⁶.

It will be realized that whereas I have described and shown a practical and operative device, nevertheless many changes might be made in the size, shape, number and disposition of parts without departing from the spirit of my invention. I therefore wish my description and drawings to be taken as in a broad sense illustrative 50 55

and diagrammatic rather than as limiting me to my specific showing.

The use and operation of my invention are as follows:

5. In order to prevent the access of dust or grit to the main bearing or to the oil, I provide a maze which makes it difficult if not impossible for particles of dust or grit to penetrate as far as the sump E^1 . Under some circumstances the 10 maze itself may be sufficient. Under other circumstances I may prefer to employ also the air delivery means above described. Thus a sheet of air may be delivered from the aperture G^2 against the inclined outer surface of the member 15 E^4 . As the air impinges against the inclined surface it will then turn and follow the surface and finally escape outwardly beneath the apron E^6 .

The oil cannot escape since it flows off through the passages E^2 from the sump E^1 . The overlap 20 of the members E and E^3 is such that by no ordinary possibility can oil escape and the oil flows off through the passages E^2 unmixed with grit or dust.

I claim:

25. 1. In a gyratory crusher including a supporting frame having a bearing surface, a head supported on said bearing for gyratory movement, means for gyrating the head, and a bowl opposed to said head; means for preventing the penetration of foreign material into said bearing including a depending apron carried by the head surrounding the bearing and terminating below the plane thereof in all positions of the head, an upwardly extending apron carried by the frame surrounding the bearing and terminating above the lower end of the head-carried apron in all positions of the head, said aprons being spaced from each other in all positions of the head, a circumferential air chamber carried by the frame 30 surrounding the frame-carried apron and having an upwardly directed annular air discharge orifice providing an upwardly directed circumferential curtain of air, a downwardly and inwardly inclined annular apron carried by the head overlying said air discharge orifice in all positions of the head for directing the circumferential curtain of air under pressure in a direction upwardly and outwardly away from said bearing.

5. upwardly directed annular air discharge orifice providing an upwardly directed circumferential curtain of air, and a downwardly and inwardly inclined annular apron carried by the head overlying said air discharge orifice in all positions of the head for directing the circumferential curtain of air under pressure in a direction upwardly and outwardly away from said bearing.

2. In a gyratory crusher including a supporting frame having a bearing surface, a head supported on said bearing for gyratory movement, means for gyrating the head, and a bowl opposed to said head; means for preventing the penetration of foreign material into said bearing including a depending apron carried by the head surrounding the bearing and terminating below the plane thereof in all positions of the head, an upwardly extending apron carried by the frame surrounding the bearing and terminating above the lower end of the head-carried apron in all positions of the head, said aprons being spaced from each other in all positions of the head, a circumferential air chamber carried by the frame surrounding the frame-carried apron and having an upwardly directed annular air discharge orifice providing an upwardly directed circumferential curtain of air, a downwardly and inwardly inclined annular apron carried by the head overlying said air discharge orifice in all positions of the head for directing the circumferential curtain of air under pressure in a direction upwardly and outwardly away from said bearing, and an outwardly and downwardly inclined circumferential apron carried by the head, said last mentioned apron being outwardly of and concentric with the downwardly and inwardly inclined apron, and cooperating therewith to finally discharge the air in a downwardly directed outwardly flaring protective curtain.

OSCAR C. GRUENDER. 40
